Myron S. Gordon, Annapolis, Md.

Application March 30, 1959, Serial No. 55,242

Term of patent 7 years

(Cl. D16—2)

FIG. 2

FIG. 3

FIG. 4

Fig. 1 is a front perspective view of a kit for testing lubricating oil contamination or the like showing my new design;

Fig. 2 is a left side elevational view thereof;

Fig. 3 is a rear elevational view thereof; and

Fig. 4 is a top plan view thereof, the bottom being substantially plain.

The dominant features of my design reside in the full line portions of the drawing.

I claim:

The ornamental design for a kit for testing lubricating oil contamination or the like, as shown and described.
